UNITED STATES PATENT OFFICE

JAMES R. ROY, OF WINNIPEG, MANITOBA, CANADA

WINDOW

Application filed June 18, 1928. Serial No. 286,255.

The invention relates to improvements in windows and an object of the invention is to provide a structure which will permit of the sashes being simultaneously raised or lowered and counter balanced in all positions and also of the swinging of both sashes into the room as and when desired, the sashes being hingedly supported from the frame during such swinging movement and being also arranged so that they can be removed entirely from the frame after they have been swung into the room.

A further object of the invention is to construct the parts in a simple, durable and inexpensive manner and so that they can be readily introduced on existing frames and sashes without materially altering either the frame or the sashes and further such that when the parts have been introduced they are not unsightly.

A more specific object of the invention is to associate racks with the sashes and pinions with the frame and engaging the racks and causing the simultaneous movement of the sashes when raised or lowered and of the counter balancing of the sashes in their various adjusted positions.

A further specific object of the invention is to provide the frame and the sashes with members which are adapted to become engaged when the sashes are both brought to a position centrally of the frame and when engaged to provide pivots for supporting the sashes and accommodating their movement during the interval they are being swung into the room.

A further specific object is to provide the frame at the side opposite to the pivot members with removable batten and parting strip sections which permit of the sashes being swung inwardly whilst carried by the pivot members aforesaid.

With the above more important and other minor objects in view, which will become more apparent as the description proceeds, the invention consists essentially in the arrangement and construction of parts hereinafter more particularly described, reference being had to the accompanying drawings, in which:—

Fig. 1 is an interior view of a window constructed in accordance with my invention.

Fig. 2 is an enlarged detailed vertical sectional view at 2—2' Figure 1.

Fig. 3 is an enlarged detailed vertical sectional view at 3—3' Figure 2.

Fig. 4 is a perspective view of one of the rack bars.

Fig. 5 is a perspective view of one of the locking catches.

Fig. 6 is a perspective view of another of the locking catches.

Fig. 7 is an enlarged detailed vertical sectional view at 7—7' Figure 2.

Fig. 8 is an enlarged detailed horizontal sectional view at 8—8' Figure 2.

Fig. 9 is an enlarged detailed face view showing the hinge leaves and other parts appearing at one side of the window frame.

Fig. 10 is an enlarged detailed horizontal sectional view at 10—10' Figure 9.

Fig. 11 is a perspective view of the locking latch of the lower sash.

Fig. 12 is an enlarged detailed vertical sectional view through the latter latch.

Fig. 13 is a vertical sectional view at 13—13' Figure 12.

Fig. 14 is a perspective view of the doubly jointed hinge employed.

Fig. 15 is a perspective view of one part of the doubly jointed hinge.

Fig. 16 is a perspective view of a portion of the hanger for the doubly jointed hinge, the hinge pin being shown in dotted outline.

Fig. 17 is an enlarged detailed horizontal sectional view through a portion of the window frame and through the sash, the frame and the doubly jointed hinge connecting the same, the sash being in the closed position.

Fig. 18 is a view corresponding to Figure 17 but with the parts shown in the position they occupy when the sashes are swung inwardly towards the room.

In the drawing like characters of reference indicate corresponding parts in the several figures.

The window frame 1 is of the conventional type and presents the inner and outer battens 2 and 3 and the intervening parting 100

strip 4 which provide vertical inner and outer guide channels 5 and 6 for the lower (inner) and upper (outer) sashes 7 and 8.

The outer battens 3 pass from the top to the bottom of the frame as does also the inner batten and the parting strip at the left hand side of the frame. The inner batten at the right hand side of the frame is provided centrally of the frame with a removable batten section 2' of a length slightly greater than the length of either sash. The section 2' when removed permits of the in-swinging into the room of the lower sash in a manner later described.

Any suitable means can be provided for detachably fastening the batten sections 2'. I have herein shown the lower end of the stationary batten provided with a locking plate 9 slidably attached thereto and having the upper end provided with a finger piece 9' and the lower end longitudinally slotted to provide three fingers 9², the central finger of which is offset laterally in respect to the other two. The locking plate is adapted to engage with a similar stationary plate 10 permanently fastened to the underlying stationary portion of the batten, the plate 10 having fingers 10' adapted upon engagement with the fingers of the sliding plate to lock the batten against removal. The upper end of the batten is supplied with a stationary plate 11 of the same form as the plate 10 and the fingers 11' thereof are adapted to pass into locking engagement with fingers 12 carried by an overlying complementary stationary plate 13 permanently fastened to the overlying lower end of the upper stationary portion of the batten. Obviously one can release the batten by raising the finger piece 9' to cause the lower mating fingers to pass out of engagement and then by pulling out the freed lower end of the batten, can withdraw the fingers 11' from those 12.

The parting strip 4 at the right hand side of the frame is also provided with a removable section 4' located centrally of the frame and also adapted when removed to permit of the in-swinging into the room of the upper sash. The removable parting strip section 50 can be held in place in any suitable manner and is herein shown as provided at the ends with sliding locking plates 15 equipped with finger pieces 15', the sliding plates being adapted to engage behind stationary plates 55 15^x secured to the stationary parts of the parting strip. The ends of the removable parting strip section are positively prevented from lateral displacement by fins 16 passing slidably through slots provided in the 60 section and entering receiving slots formed in the window frame (see Figure 8).

The removable section of the parting strip is provided centrally of its length with a pinion 17 which has a diameter somewhat 65 greater than the width of the parting strip

so that the pinion protrudes into the adjacent channels 5 and 6. According to the present construction, I have divided the removable section of the parting strip and reunited the parts thereof by a special casting 18 which is fastened by screws 18' to the parting strip section parts and is provided centrally with a cross slot which receives the pinion, the pinion being rotatably mounted on a screw 18^x passing centrally across the slot. The casting is supplied with legs 18² which are adapted to enter receiving pockets formed in the face of the window frame and preventing lateral springing of the central portion of the removable parting strip section.

The sashes are both provided with similar rack bars 19 and 19' of the form best shown in Figure 4.

The rack bars extend longitudinally of the sashes and are counter sunk in one of the edges thereof and fastened thereto by screws passing through suitably positioned lugs 19^x provided on the bars. The teeth of the rack bars are continuously in mesh with the opposite sides of the pinion in the manner best shown in Figure 2 and according to this arrangement, it will be obvious that the sashes counter balance one another through the pinion and that upon the lower sash being raised, the upper sash will move down an equal amount and vice versa. The pinion is located centrally of the length of the frame and accordingly when the sashes are brought to a position centrally of the frame, that is, one directly behind the other, the right hand sides of the sashes can be swung inwardly of the room provided the removable batten section and removable parting strip section be taken out.

In order that there may be no binding action occasioned when the sashes are sliding in the frame, I have provided the left hand sides of the sashes with rack bars identical to those at their right hand sides and the left hand parting strip with a pinion engaging such rack bars. As such structure is merely the duplication of that previously described, a further description is not given.

Means are provided for pivotally supporting the sashes at the left hand side of the frame and at the time they are to be swung inwardly into the room and such are designed to in no way interfere with the vertical sliding movement of the sashes in the window frame.

To the left hand side of the frame, I secure a pair of similar hinge wings 20 and 20', these being spaced a predetermined distance apart and having the bases thereof counter sunk in the frame and partially underlying the inner batten 2 at that side of the frame. Each hinge wing is provided with an arm 20^x positioned at right angles to the face of the frame and located to the

side of the channel 5 and each arm carries a downwardly extending hinge pin 21, the lower end of which is pointed.

To the left hand side of the lower sash 5 is fastened a pair of spaced hinge wings 22 and 22' and these are both provided with extending vertically aligned sleeve like bearings 23 and 23' which are adapted in the up sliding movement of the lower sash in the frame to receive the pivot pins 21, such occurring when the inner sash has been brought to a position where it can be swung into the room upon the removal of the inner batten section 2'.

In order to prevent the dropping of the sash as it is being swung into the room, I have provided the lower wing 22 with a spring pressed locking latch 24 which in the raising movement of the inner sash is adapted to slide over the pin and arm of the wing 20' and then become caught over the upper side of the said arm. In other words, when the inner sash has been brought to the position where it is to be swung into the room, the bearing sleeve 23 is on the pin of the lower wing 20' and the latch 24 is overlying the arm of the wing. Consequently the sash cannot fall when it is swung inwardly of the room as it is supported by the latch and swivels on the pins 21.

The latch is herein shown as projecting from a casing 25 carried by the wing 22 and as provided with an arm 24' connected by a pin 24^x carried by the upper forked end of a lever 26. The lever is pivotally mounted on a cross pin 26' carried by the casing and has the lower end thereof also forked. A spring 27 engages the casing and the lever and normally presses the lever in a direction which holds the latch normally in the position best shown in Figures 11 and 12 of the drawings. The casing carries also an extending pivoted finger piece 28 which has an extending finger 29 engageable with the cross web 26^x of the lever.

The arrangement is such that when the finger piece is down pressed, the latch is drawn into the casing and can be cleared from the upper end of the arm 20^x of the wing 20'. According to this arrangement, one can remove the lower sash if he so desires after it has been swung into the room and further one can release the sash for vertical sliding movement within the frame after it has been swung back into the frame.

Provision is also made for pivotally supporting the upper sash during the interval that it is being swung into the room and also for permitting the said sash to be removed from the frame after it has been swung into the room. The said means embodies two identically constructed doubly jointed hinges fastened to the upper sash and two identically constructed hangers permanently fastened to the window frame. As the said hinges and

hangers are identically constructed, a description of one will suffice.

Each hinge embodies a central wing 30 and two side wings 31 and 32, the several wings being pivotally connected in the well known manner by pivot pins 33 and 34. The wing 31 is permanently fastened by screws 31' to the outer face of the upper sash and has one edge thereof turned outwardly to provide a hook 35 and the other edge thereof turned inwardly as indicated at 36 and carrying eyes 37 for the hinge pin 33 which pin is located centrally of the width of the sash. The central wing 30 is substantially T-shaped in horizontal cross section and carries two sets of eyes 38 and 39, those 38 being complementary to the eyes 37 and receiving the pin 33. The wing 32 is provided at one edge with aligned spaced eyes 40 adapted to pass between the eyes 39 and to receive the hinge pin 34 and at the other edge with a single comparatively large eye 41 positioned at the upper end of said wing.

When the upper sash is in its vertical sliding position within the frame, the wings of the latter hinges are folded together in the manner best shown in Figures 14 and 17, the wings 30 at such time moving up and down with the sash within the channel 6 and here it will be observed that the wing 31 is provided with an offset 42 to receive, in the folded position of the wings, the transverse head like portion 30' of the wing 30 and that the eye 41 is caught in the hooks 35 of the wing 31 and is accordingly prevented from swinging around the pivot pin 34.

The hangers 43 and 44 carried by the frame and which receive the eyes 41 of the doubly hinged wing are as before stated identically constructed and they are positioned on the frame such that when the upper sash has been brought to the position where it is swung inwardly into the room, the hinges thereof will be received by the hangers. Each hanger embodies a substantially rectangular plate 45 counter sunk in the base of the channel 6 and fastened thereto by screws 45' and the plate is provided at the outer edge with a substantially Z-shaped extension 46 which fits around the adjacent edge of the batten 3 and carries a flange 47 disposed at right angles to the face of the batten and terminating in a relatively large lower eye 48 complementary to the eye 41. The eye 48 receives a hinge pin 49 which is permanently fastened thereto and which is adapted to enter the eye 41 to attach the sash hinged to the frame. The upper end of the hinge pin is pointed so that it will readily pass into the eye 41 when the upper sash is moved down within the frame.

The upper end of each eye 48 is provided with a stop shoulder 50 and above this with an upwardly spiralling face 51 and the eye 41 has the lower end provided with a spiralling face 52 complementary to that 51 and

with a shoulder 53 engageable with the shoulder 50 and the arrangement is such that when the upper sash is being swung into the room, the eye 41 will be caused to move upwardly 5 on the pivot pin 49 due to contacting spiraling faces 51 and 52 and the shoulders 50 and 53 will come in contact and prevent the outward buckling of the joint at the pin 43.

To make this latter clear, I refer to Figure 18 and it will be observed that unless prevented, it would be possible for the wing 32 to swing in the direction indicated by the applied arrow which would make it difficult to replace in the frame the inswinged sash. The 15 shoulders 50 and 53 are designed to come in contact and prevent the swinging of the wing 32 further than a predetermined distance in the direction of the applied arrow Figure 18.

As aforesaid, when the upper sash has been 20 swung into the room, it has been raised slightly due to the inclination of the engaged faces 51 and 52 and accordingly when one is desirous of replacing the upper sash in the frame, the eyes 41 have a natural tendency 25 to gravitate downwardly and rotate in a direction opposed to the direction of the arrow Figure 18 which causes the said wings 32 to initially fold in towards their original positions as shown in Figure 17. Subsequently 30 the upper sash is swung into the frame turning on the pivots 34 and 33, the hinged parts finally taking the position shown in Figure 17.

It is here pointed out that the flange 47 35 is provided on the inner side with a lengthwise extending channel 54 (see Figures 17 and 18) and this channel provides a clearance space for the eyes 39 and 40 to swing into when the upper sash is being initially swung 40 into the room and that the inner ends of the rack teeth of the inner sash as well as the inner corner of the inner sash are slightly beveled off to allow them to escape the parting strip when the said lower sash is being 45 replaced in the frame.

The above completes the description of the parts and in order that the invention may be better understood, I will now describe the manner in which it is used. When one wishes 50 to ventilate a room, he raises the lower sash and this causes through the racks and pinions, the down movement of the upper sash an equal amount and as the sashes are approximately of equal weight, they counter balance 55 one another through the pinions. If it is desired to open or swing the inner sash into the room, it is only necessary to raise the lower sash to a central position within the frame, then take out the removable batten 60 section 2' and subsequently swing the said sash into the room at which time the sash is turning on the pins 21 and is prevented from falling by the latch 24. If it is desired to entirely remove the sash from the window, 65 one has simply to depress the finger piece 28

to release the latch and this allows the eyes 23 23' to slide downwardly off the pins 21.

If it is desired to swing the upper sash into the room, the inner sash is swung into the room in the manner just described and having done this, one then removes the parting strip section 4' and swings the upper sash into the room, the hinges thereof permitting such movement and taking the final position as shown in Figure 18.

One can then remove both sashes from the frame if they so desire by releasing the latch 24 of the inner sash and by lifting the upper sash clear of the pivot pins 49. To reset the removed sashes back into the frame, it is only necessary to reverse the above operations and the hinges provided accommodate the movement, those for the upper sash folding back into the position shown in Figure 17.

What I claim as my invention is:—

1. The combination with a window frame, of vertically extending battens and parting strips secured to the sides of the frame and forming vertical guideways and having centrally located removable sections at one side of the frame, upper and lower sashes slidably mounted in the guideways, rack bars secured to the sashes and located in pairs at opposite sides of the parting strips, pinions rotatably carried by the parting strips and engageable with the pairs of rack bars aforesaid, said pinions being located centrally of the frame and one of said pinions being removable with the removable parting strip section and said removed parting strip and batten sections permitting of the inswinging of the sashes upon the sashes being brought to a central position in respect to the frame and engaging hinge sections carried by the frame and the sashes, said hinge sections becoming engaged when the sashes are brought to a central position within the frame and being adapted to support the sashes when swung inwardly as aforesaid.

2. The combination with a window frame, of vertical battens and parting strips carried by the frame and forming vertical guides, the parting strip and the inner batten at one side of the frame having removable centrally located sections, upper and lower sashes slidably mounted in the frame and inwardly swingable upon the latter batten and parting strip sections being removed, pairs of opposing rack bars permanently secured to the edges of the sashes, pinions located centrally of the sides of the frame and carried by the parting strips and continuously engaging the adjacent rack bars of the sashes, hinge forming members carried by the frame and the inner sash, said members being adapted to come into engagement upon the inner sash being raised to a central position within the frame, means releasably locking the hinge members engaged and hinge forming sections carried by the upper sash and the frame

and adapted to come into engagement and support the upper sash when the same is brought to a central position in respect to the frame, all the said engaged hinged members being adapted to support the sashes upon the removable batten and parting strip sections being removed and the sashes swung inwardly of the room.

3. The combination with a window frame, 10 of vertically extending battens and parting strips secured to the sides of the frame and forming vertical guideways and having centrally located removable sections at one side of the frame, upper and lower sashes slidably mounted in the guideways, rack bars secured to the sashes, a pinion rotatably carried by one of the parting strips and engaging the rack bars, said pinion being located centrally of the frame and said removable 15 parting strip and batten sections permitting of the inswinging of the sashes upon the sashes being brought to a central position in respect to the frame and extending engageable hinge sections carried by the frame and 20 the sashes, said hinge sections becoming engaged when the sashes are brought to a central position within the frame and being constructed to support the sashes when swung inwardly as aforesaid.

25 30 Signed at Winnipeg, this 28 day of March, 1928.

JAMES R. ROY.
